SPRING SCALE

Filed June 6, 1929

UNITED STATES PATENT OFFICE

SYLVESTER G. AVERELL, OF NEW YORK, N. Y., ASSIGNOR TO JOHN CHATILLON & SONS, OF NEW YORK, N. Y., A CORPORATION OF NEW YORK

SPRING SCALE

Application filed June 6, 1929. Serial No. 368,856.

This invention relates to spring scales and more particularly to a novel construction whereby the weight is suspended directly from the hanger portion of a frame so that 5 the axis of the scale will always assume a vertical position under all conditions of use.

A primary object of the invention is to provide a stamped metal scale frame including a hanger by which the scale and the load 10 responsive springs are supported in such a way that there is no lateral distortion of the frame under load, thus permitting of the use of relatively thin gauge metal which not only effects economy in the making of the scale, 15 but contributes materially to the lightness thereof, while at the same time permitting of shaping the frame in such a way that added stiffness and strength is imparted to the entire structure.

20 Another object of the invention is to provide novel means for maintaining the rack in engagement with the pinion on the indicator shaft so that a uniform engagement between the rack and the pinion will be maintained for all positions of the rack during its movement.

A further object of the invention is to provide novel means on the frame concentric with the axis of the indicator shaft to insure 30 the mounting of the dial plates accurately with reference to the axis of the indicator shaft.

With the above and other objects in view which will more readily appear as the nature 35 of the invention is better understood, the same consists in the novel construction, combination and arrangement of parts herein-after more fully described, illustrated and claimed.

40 A preferred and practical embodiment of the invention is shown in the accompanying drawings in which:—

Figure 1 is a front elevation of a scale embodying the present improvements.

45 Fig. 2 is an elevation of the novel stamped metal frame and its associated parts, the casting of the scale being removed to better illustrate the same.

50 Fig. 3 is an enlarged vertical cross-sectional view taken on the line 3—3 of Fig. 2.

Fig. 4 is a horizontal cross sectional view taken on the line 4—4 of Fig. 2.

Similar reference characters designate corresponding parts throughout the several figures of the drawings.

The frame for suspending and carrying the entire scale mechanism is designated generally as F and includes a hanger H provided with a suitable opening or eye for receiving a hook or its equivalent to suspend and support the scale. The body of the frame F is provided at its intermediate portion with a horizontal offset shoulder or shelf A which is intersected by the plane of the hanger portion H and provides at opposite sides of this plane the equi-distantly spaced sections or walls B and C. The lower end D of the frame is bent inwardly and is provided with an opening for receiving the struck-up portions E of the ring or casing G of the scale 70 housing.

As will be observed from Fig. 2, the said hanger H is provided with the shoulder portion I for engaging with the inside of the ring G so that the said ring will be engaged 75 at diametrically opposite points by the top and the bottom of the frame, thus centering the ring and maintaining it in position in such a way that it receives or carries none of the load imposed on the scale.

Referring to the intermediate offset portion A of the body of the frame F, it will be observed from Figs. 2, 3 and 4 that the same is cut or slit to permit of the formation of down-turned wings 1 which not only serve as a means for transversely bracing the upper and lower walls B and C but also provide clearance for the main loading springs S of the scale to facilitate their attachment to the runner M. The horizontal web 2 of the offset intermediate portion A is also provided with an opening 3 for guiding the rack R. The lower end of the upper wall B of the frame has attached thereto a journal plate 4, the same being suitably secured to the wall as indicated at 5 and extending downwardly into the zone of the wings 1 where it is provided with an opening 6 for receiving one end of the indicator shaft 7, the opposite end of which is journaled in the opening 8 formed in the 100

lower wall C. Both the journal plate 4 and the wall C adjacent the openings 6 and 8 are provided with hub portions 9 to facilitate the centering of the dial plates 10. In the assembling of the device the dial plates 10 forming the opposite sides of the scale are preferably placed on the hubs 9 and then the ring G, which is split, is placed around the peripheral edges of the members 10 and against the top and bottom ends of the frame F as previously indicated so that it may be secured to complete the final assembly of the scale.

The runner M is suspended by the springs S directly from the top of the hanger H so that the runner moves in the same vertical plane as the hanger H. Thus, the entire weight of the load imposed on the runner is directly suspended from the hanger portion and none of the remaining parts of the frame or the scale housing are subjected to any of the load being weighed by the scale.

The runner M has mounted thereon an adjustable rack carrier bar N, the same being provided at its lower end with a horizontal offset portion 11 for receiving a screw 12 whose upper end engages with the offset lip 13 formed from the guide strap 14 of the runner whereby the turning of the screw 12 will move the bar N upwardly or downwardly according to the direction in which the screw is turned. The offset 11 of the bar N is urged against the head of the screw 12 by the spring 15. The upper end of the bar N is pivotally connected to the rack R by a suitable pivot 16 so that as the runner moves under varying loads, the rack will freely engage the indicator pinion 17 on the shaft 7 and thus move the indicator hands 18 carried on the ends of the shaft 7 to indicate or register the load being weighed by the scale.

In connection with the rack R it is pointed out that the same is preferably made of a material having a higher co-efficient of expansion than the springs S as fully described and claimed in my co-pending application, Serial No. 368,852, filed of even date herewith. However, the novel frame F and its associated parts may be used in connection with various types of racks and runners as will be readily apparent, since as previously indicated, the stamped metal frame constitutes the principal novel feature of the present case.

A feature of practical importance in maintaining the accuracy of the scale is that of providing means for accurately and reliably maintaining the rack R in engagement with the pinion 17, such means comprising a spring 19 whose intermediate portion is looped as at 20 and its lower end 21 is held in the struck-out portions 22 of the frame. The upper free end 23 of the spring 19 is located directly opposite the axis of the pinion 17 and is provided with an offset end portion 24 which is guided in a suitable opening 25 in one of the

wings 1 of the intermediate offset portion A of the frame. The construction of the spring 19 is such that under changing temperatures as well as the frictional engagement with the rack, the portion 23 thereof will always be maintained in the proper position, that is, in a horizontal plane intersecting the axis of the pinion 17.

From the foregoing it will be apparent that the present invention provides a simple and practical form of stamped metal frame on which all of the moving parts of the scale mechanism may be assembled as well as the exterior casing, the latter however being entirely free from loading strains or stresses, and the load itself being supported directly from the hanger of the frame so that none of the frame except the top thereof is subjected to load conditions.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. In a spring scale, a stamped metal scale frame having a hanger lying in a vertical plane with offset and depending sections suitable for mounting the scale mechanism thereon.

2. In a spring scale, a stamped metal scale frame having a hanger lying in a vertical plane with offset and depending sections suitable for mounting the scale mechanism thereon, said offset and depending sections being free from scale load.

3. In a spring scale, a stamped metal scale frame having a hanger lying in a vertical plane with offset and depending sections suitable for mounting the scale mechanism thereon, the material of the frame being so disposed that when the assembled scale is suspended from the hanger the axis of the scale will assume a vertical position.

4. In a spring scale, a stamped metal scale frame having a hanger lying in a vertical plane with offset and depending sections suitable for mounting the scale mechanism thereon, the material of the frame being so disposed that when the assembled scale is suspended from the hanger, the axis of the scale will assume a vertical position and the offset and depending portions will be free from scale load.

5. In a spring scale, the combination with a casing, of a frame including a hanger and an intermediate horizontal portion forming offset vertical walls arranged in planes at opposite sides of said hanger, springs carried by the hanger, a runner arranged in the

plane of the hanger and springs connecting the hanger and the runner.

6. In a spring scale, the combination with a casing, of a frame including a vertical hanger and an intermediate horizontal portion forming vertical walls located at opposite sides of the plane of said hanger, a runner mounted to move in the plane of the hanger, springs connecting the hanger and 10 the runner, an indicator shaft journaled in said intermediate horizontal portion, a pinion on said shaft, and a rack carried by the runner and operatively engaging with said pinion.

15 7. In a spring scale, the combination with a casing, of a balanced frame arranged within the casing, an intermediate stiffened portion formed in the frame, an indicator shaft mounted in said stiffened portion, springs 20 carried by the top of the frame, a runner suspended from said springs whereby the load imposed on the runner and springs will be supported entirely from the top of the hanger and top of the frame and independently of 25 the other portions of the frame and the casing.

8. In a spring scale, a stamped metal frame including an intermediate offset portion forming upper and lower offset vertical walls, 20 means in said offset portion for forming a journal for the indicating shaft, said means including outwardly projecting hub portions, and dial members adapted to be centered on said hub portions.

35 9. In a spring scale, a stamped metal frame including a hanger portion, an intermediate offset portion and upper and lower walls arranged at opposite sides of the offset portion, said offset portion including down 40 turned wings and provided with a rack receiving slot in the top wall thereof, and said slot being in line with the hanger portion of the frame, a journal plate carried by the upper wall of the frame and having a journal 45 opening registering with a journal opening in the lower wall of the frame, an indicating shaft mounted in said journeled openings, springs mounted on the hanger portion of the frame and paralleling the sides of the said 50 wings, and a runner suspended in said springs.

In testimony whereof I hereunto affix my signature.

SYLVESTER G. AVERELL.
